UNITED STATES PATENT OFFICE.

WILHELM GRAAFF, OF BERLIN, GERMANY.

ICE-MAKING MACHINE.

1,079,334.

Specification of Letters Patent. Patented Nov. 25, 1913.

Application filed September 28, 1911. Serial No. 651,897.

To all whom it may concern:

Be it known that I, WILHELM GRAAFF, merchant, a subject of the German Emperor, and residing at 17 Linkstrasse, Berlin, W. 5 9, in the Kingdom of Prussia, Germany, have invented certain new and useful Improvements in Ice-Making Machines, of which the following is a specification.

The present invention relates to ice making machines of the type, in which the refrigerating medium is separated in a vessel from a solution by means of evaporation, then again condensed in a second vessel, thereupon reevaporated under action of a 10 vacuum and finally again absorbed by an absorbent substance in the first vessel. A machine of this type is described for instance in the U. S. Patent 958,683. In this known machine metal plates or disks 15 are arranged in both absorber and refrigerator with the object of promoting the conduction of the heat into and from the interior of the machine, of increasing the absorbing and evaporating surfaces and of 20 acting as agitators on the machine being rotated and preventing the liquid from being carried from one vessel into the other.

It has been found in machines constructed with flat disks that too great a quantity of 25 the absorbing medium will remain in the refrigerator, when the latter is raised above the absorber. In order to avoid this difficulty the disks in the machine constructed according to the present invention are made 30 of a funnel-like shape, which will when the machine is tilted back so that the refrigerator is above the absorber, insure a good return of the absorbing medium into the absorber.

40 In the accompanying drawing a constructional form of the machine according to the present invention is shown in diagram and in part section. In this drawing *a* is the absorber and *b* is the refrigerator of the 45 machine. Both vessels communicate through the pipe *c*, which is perforated with holes *d* and at the same time serves for allowing of rotating the machine in suitable bearings *e*. Both vessels are evacuated after 50 the absorbing and the refrigerating medium

have been introduced, and the vessels are thereupon permanently closed and sealed in a hermetical manner. Within the two vessels the perforated disks *f* are arranged—in contact with the walls of the vessels; 55 these disks have a funnel or dishlike shape and a tubular socket *g* on which if necessary a bead *h* may be provided, particularly on the disks in the absorber. These tubular sockets of sleeves *g* and bead *h* 60 tend to prevent the liquid carried by the disks during the rotation, from dripping down on the hollow shaft and thence finding its way into the refrigerator where its presence would interfere with the operation of 65 the refrigerator. The disks in the refrigerator are turned with their socket *g* toward the entrance opening of the tube *c*. Therefore the absorbing medium will, when 70 it has been conveyed into the refrigerator by lifting the absorber *a*, flow back easily into the absorber when the refrigerator is lifted, so that only a small quantity of the 75 absorbing medium will remain in the refrigerator. In consequence of their funnel-like shape the disks *f* furthermore offer a greater evaporating and absorbing surface than the known flat disks and their mixing effect is also greater than that of the flat disks. 80

I claim—

1. In an ice making machine the combination of a vessel serving as distiller and absorber with a vessel serving as condenser and refrigerator, a tube connecting said vessels, passing through the absorber and having perforations within the same and serving as a revolving shaft for said vessels, a plurality of conical, perforated disks in the absorber, said disks having a tubular socket. 85

2. In an ice making machine the combination of a vessel serving as distiller and absorber with a vessel serving as condenser and refrigerator, a tube connecting the two 95 said vessels, passing through the absorber and having perforations within said absorber said tube serving as a common revolving shaft for said vessels, a plurality of conical disks with perforations mounted 100

in the absorber, said disks each having a central tubular socket, provided with a bead at the free end, and similarly shaped perforated disks each having a central tubular socket in the refrigerator, said disks in the absorber all turned with their apices toward said refrigerator and said disks in the ab- sorber all turned with their apices toward said absorber.

WILHELM GRAAFF.
